FIG. II.

FIG. IV.

Inventor
by Truman W. Post
Chester H. Braselton

Attorney

UNITED STATES PATENT OFFICE.

TRUMAN W. POST, OF PROVIDENCE, RHODE ISLAND, ASSIGNOR TO WILLYS CORPORATION, OF TOLEDO, OHIO, A CORPORATION OF DELAWARE.

HEADLIGHT.

1,416,235.

Specification of Letters Patent. Patented May 16, 1922.

Application filed September 12, 1917. Serial No. 190,974.

To all whom it may concern:

Be it known that I, TRUMAN W. Post, a citizen of the United States, residing at Providence, in the county of Providence and 5 State of Rhode Island, have invented certain new and useful Improvements in Headlights, of which I declare the following to be a full, clear, and exact description.

This invention relates to headlights and 10 more particularly to automobile headlights of the type provided with a tilting reflector whereby the beam of light from the headlight may be deflected downwardly upon the ground in front of the vehicle, in order 15 to prevent objectionable glare.

An object of this invention is to provide an improved headlight construction of such a nature that the parabolic shape of the tilting reflector will be maintained. A further object of my invention is to provide 20 simple and convenient means for mounting the reflector within the casing so that it will swing on a horizontal axis. A still further object of my invention is to provide a headlight construction, having a tilting reflector, in which spring-mounted bearings are 25 provided for the reflector trunnions so as to eliminate rattle and objectionable noise due to vibration of the headlight. 30 Further objects, and objects relating to economies of manufacture and details of construction, will definitely appear from the detailed description to follow:

I accomplish the objects of my invention 35 in one instance by the devices and means described in the following specification, but it is evident that the same may be varied widely without departing from the scope of the invention as pointed out in the appended claims.

A structure constituting a preferred embodiment of my invention is illustrated in the accompanying drawings, forming a part of this specification, in which:

45 Figure I is a vertical, sectional view, taken through a headlight embodying my invention, the reflector being shown by dotted lines in its tilted position in which the beam of light is deflected downwardly 50 upon the ground.

Figure II is a vertical, sectional view, taken substantially on the line II—II of Figure I, portions of the reflector adjacent the forward edge thereof, being shown in 55 section in order to illustrate the manner in

which the reflector trunnions are mounted, and

Figure III is an enlarged, fragmentary, detail, sectional view, taken substantially on the line III—III of Figure II and showing 60 one of the reflector trunnions and its bearing.

In the drawings, similar reference numerals refer to similar parts throughout the several views and the sectional views are 65 taken looking in the direction of the arrows at the ends of the section lines.

Considering the numbered parts of the drawing, I have shown a headlight comprising a casing 10, a ring 11 secured to the 70 forward end of said casing, and a lens 12 carried by said ring and closing the open front end of the headlight casing. A reflector 13 of the parabolic type is provided, which reflector carries a socket 14, having a 75 light bulb 15 so mounted that the filament is located substantially at the focus of the reflector. A connector 16 is carried by the rear of the headlight casing and connected by wires 17 with the socket 14. The forward edge of the reflector is rolled around a wire 18, forming a bead 19 at the forward edge of the reflector. This insures the forward edge of the reflector remaining truly circular so that the true parabolic shape of 85 the reflector is always maintained.

At diametrically opposite points a pin 20 is inserted through the bead 19 and the wire 18 and secured thereto in any suitable manner, these pins forming trunnions for the 90 reflector. At diametrically opposite points a spring strip or arm 22 is secured to the casing 10 by rivets 21 and these spring strips or arms carry, in their free ends, bushings 23 in which the reflector trunnions may be 95 journaled. These spring strips carrying the trunnion bushings are preferably located at diametrically opposite points on the casing, such that the reflector is journaled on a horizontal axis. It is evident that parts of the 100 pivoting means may be carried by the casing and coacting parts thereof carried by the reflector as may be desired, the spring support 22 serving in all cases to absorb vibrations incident to a rapidly moving vehicle. 105

A clip 24 embraces the rear end of the socket 14 between the reflector 13 and the casing 10 and said clip is connected to a wire 25 which extends downwardly through the casing 10 and the sleeve 26 projecting 110

through the casing 10 and through a boss 27 secured to said casing. The sleeve 26 is adjustably mounted in said boss and is secured in the adjusted position by means of 5 the set screw 28. The wire 25 may extend to any suitable or convenient place from which it may be manipulated to tilt the reflector from one position to the other.

I am not concerned in my present application with the mechanism for tilting the reflector and this showing is merely illustrative of one method of tilting the reflector and any other method of swinging the reflector on its axis may be used without departing 10 from the spirit of my invention, which has to do with the pivotal mounting of the reflector within the casing.

From the description of the parts given above, the operation of my device should be 20 very readily understood. The parabolic reflectors, which are commonly used in automobile headlights, are made of very light gauge metal, which is comparatively flexible in the sheet form. The inner surface of this 25 reflector is highly polished and it is essential that the parabolic shape of the reflector be maintained, as otherwise the rays of light reflected from it will not travel in parallel lines in accordance with the theory of the 30 parabolic reflector.

On account of the lightness and flexibility of the metal used in making these reflectors, it is extremely difficult to preserve their 35 parabolic form, unless means are provided for maintaining the outer edge of the reflector as a true circle. In headlights of the stationary reflector type this is usually accomplished by clamping the outer rim of the reflector between the headlight casing and 40 the front ring holding the lens, but where the reflector is mounted to tilt in the casing, this construction is impossible and some other means must be provided for maintaining 45 the parabolic shape of the reflector.

In my present invention, I accomplish this 50 by rolling the forward edge of the reflector around a circular wire 18, thus forming a peripheral bead 19 reinforced by the wire 18 around the forward edge of the reflector. This construction not only serves to stiffen 55 and reinforce the reflector so as to maintain its parabolic shape, but it also forms a very convenient and simple mounting for parts of the pivot for the reflector such as the trunnions, which comprise the pins 20 set into and secured to the bead 19 and the wire 18.

An automobile headlight is subject to a great deal of vibration as the automobile is driven over rough or uneven surfaces and it 60 is absolutely essential, in order to provide a headlight construction that is commercially practicable, that the headlight should be so constructed that all rattle shall be eliminated. In order to further this end, I provide 65 bearings for the reflector trunnions

which are spring-mounted, the bushings 23 being mounted in the strips 22 of spring metal, the whole forming one type of flexible or resilient mounting for the reflector. This not only provides a mounting for the trunnion bearings, which will prevent any rattle thereof, but it also provides a very simple and convenient method for mounting or dismounting the reflector, as the spring strips 70 22 may be sprung to one side against their spring tension so as to free the trunnion 20 from the bushing 23. Moreover, the springs 22 on opposite sides of the casing tend to 75 yieldingly support the pivots for mounting the reflector therein. 80

I am aware that the particular embodiment of my invention, which I have here shown and described, is susceptible of considerable variation without departing from the spirit thereof and, therefore, I desire to 85 claim my invention broadly as well as specifically, as indicated by the appended claims.

Having thus described my invention, what I claim as new and desire to secure by Letters Patent, is:

1. A device of the class described, comprising the combination of a casing; a reflector; a wire bent to the form of a circle and disposed at the forward periphery of said reflector, the forward edge of said reflector being bent around and embracing said wire to form a stiffening bead; reflector trunnions set into and secured to said wire and stiffening bead; and bearings for said 95 trunnions carried by the casing.

2. A device of the class described, comprising the combination of a casing; a reflector; trunnions carried by said reflector; and spring metal strips secured to said casing, each of said trunnions having a bearing in the free end of one of said spring strips. 105

3. A device of the class described, comprising the combination of a casing; a reflector; a pair of trunnions carried by said reflector at diametrically opposite points thereof; spring arms secured to said casing; and bearings for said trunnions carried by said arms and disposed at diametrically opposite points in said casing. 110

4. A device of the class described, comprising the combination of a casing; a reflector; a pair of trunnions carried by said reflector at diametrically opposite points; 120 spring arms secured to said casing and bushings carried by the free ends of said arms in which said trunnions may be journaled.

5. A device of the class described, comprising the combination of a casing; a reflector; a wire bent to circular form and disposed adjacent the forward end of said reflector; said forward edge being rolled around said wire, forming a stiffening bead; a pair of trunnions carried by said wire at 130

diametrically opposite points; and a pair of spring arms secured to said casing, and each provided with a bushing, in which one of said trunnions may be journaled.

5 6. A device of the class described, including in combination, a casing, a reflector, parts of pivoting devices carried by said reflector, spring means connected at one end to said casing, and co-acting parts of said 10 pivoting devices located in the free end of said spring means.

7. A device of the class described, including a casing, a reflector, a wire bent to form a circle disposed at the forward periphery 15 of said reflector, the forward edge of said reflector being bent around and embracing said wire to form a stiffening bead, parts of reflector pivoting devices set into and carried by said wire and stiffening bead, 20 and co-acting parts of said pivoting devices carried by said casing.

8. In a device of the class described, the combination of a casing, a tiltable light reflector mounted in said casing, means for pivotally mounting said reflector in said 25 casing, and resilient means to cushion lateral movement of said reflector relative to said casing.

9. In a device of the class described, the combination of a casing, a tiltable light reflector mounted in said casing, a plurality of pivots for supporting said reflector and resilient means for yieldingly connecting said pivots and said casing.

10. In a device of the class described, the 35 combination of a supporting casing, a reflector therein, pivots for mounting said reflector in said casing and resilient members between said casing and said reflector for cushioning lateral movement of the latter. 40

In testimony whereof I affix my signature.
